UNITED STATES PATENT OFFICE.

JOHN J. SCHILLINGER, OF NEW YORK, N. Y.

CONCRETE PAVEMENT.

SPECIFICATION forming part of Letters Patent No. 256,383, dated April 11, 1882.

Application filed March 1, 1882. (No specimens.)

To all whom it may concern:

Be it known that I, JOHN J. SCHILLINGER, a citizen of the United States, residing at New York, in the county and State of New York, have invented new and useful Improvements 5 in Concrete Pavements, of which the following is a specification.

This invention relates to a concrete pavement which is an improvement on the concrete pavement described in Letters Patent Reissue No. 4,364, granted to me May 2, 1871, the object of my present improvement being to render such pavement practicable for streets. For this purpose I construct my new pavement 15 with grooves running transversely across the street from curb to curb, so as to afford a good foothold for horses and other draft-animals. I also form my pavement on a convex bed, so that when the cement has set and a portion of 20 the bed should be washed away the pavement, which forms an arch, will still retain its position against a considerable pressure.

In the accompanying drawings, Figure 1 represents a plan or top view of a street-crossing 25 provided with my pavement. Fig. 2 is a transverse vertical section in the plane $x-x$, Fig. 1. Fig. 3 is a longitudinal vertical section in the plane $y-y$, Fig. 1, on a larger scale than the previous figures.

Similar letters indicate corresponding parts.

In the drawings, the letter A designates the roadway of a street. B B are the sidewalks, and C C the curbs. The space between the curbs contains my new pavement, which is laid 35 in sections D, as described in my Patent Reissue No. 4,364, above named, each section being provided with chamfered edges $a-a$, as shown in Fig. 3, so that when the pavement is complete V -shaped channels b extend transversely 40 across the street from curb to curb. At the street-crossing A' the V -shaped channels of my pavement cross each other, as shown in Fig. 1. Of course the groove can be made of any other form; but I prefer the V shape, because

the dust does not settle therein as firmly as it would in rectangular grooves.

In laying my pavement I prepare the bed E so as to present a convex surface, and on this bed I spread the cement, either in molds or between movable joists of the proper thickness, 50 and before the blocks have set I chamfer their edges, so as to produce the V -shaped channels. By making the bed convex my pavement, when ready, forms an arch, which abuts against the curbs, and if the bed should be partially washed 55 away from under the pavement, my pavement is still able to sustain a considerable weight without giving way. For this reason I am enabled to build my pavement on a removable center or foundation when such is desirable. 60

The pavement described in my Patent Reissue No. 4,364 was intended particularly for sidewalks or walks used solely by pedestrians, and on account of its smooth surface I could not apply the same to the roadways of streets. 65 By my present improvement the pavement is rendered eminently fit for roadways.

I distinctly disclaim in my present application everything shown and described in my Patent Reissue No. 4,364.

What I claim as new, and desire to secure by Letters Patent, is—

1. A concrete pavement for roadways, laid in sections and provided with grooves extending transversely across the roadway from curb to curb, substantially as shown and described. 75

2. A concrete pavement for roadways, laid in sections on a convex bed or foundation and extending from curb to curb, substantially as set forth. 80

In testimony whereof I have hereunto set my hand and seal in the presence of two subscribing witnesses.

JOHN J. SCHILLINGER. [L. S.]
